UNITED STATES PATENT OFFICE.

JOHN POUNTNEY UDAL, OF BIRMINGHAM, ENGLAND.

PRESS GUARD.

Application filed July 28, 1924. Serial No. 728,745.

To all whom it may concern:

Be it known that I, JOHN POUNTNEY UDAL, a British subject, residing at 91 Oakfield Road, Selly Park, in the city of 5 Birmingham, England, have invented certain new and useful Improvements Relating to Press Guards, of which the following is a specification.

The invention has for its object to provide 10 an improved hand guard for such machines as presses, stamps, hammers, and the like, the guard being of the type in which an oscillatory lever system, actuated by the plunger or other moving part, is caused to move in a direction at right angles to the front of the machine.

The invention comprises the combination 20 of a carrier lever or lever system pivoted on a stationary part of the machine and adapted to receive motion from the machine, a lever or lever system provided with a hand striking member and pivoted on the first mentioned lever or lever system, and constraining means attached to the machine 25 and to the second mentioned lever or lever systems, the arrangement being such that the said striking member is caused to move through a curvilinear path.

In the two accompanying sheets of explanatory drawings:—

Figure 1 is a sectional side elevation showing a press guard constructed in accordance with this invention.

Figures 2 and 3 are front elevations showing the guard in the inoperative and operative positions respectively.

Figure 4 is a diagrammatic side view showing a modification of the hand guard lever.

Figure 5 is a diagrammatic side view showing a modification of the constraint acting on the hand guard lever.

Figure 6 is a similar view to Figure 5 showing a further modification.

In applying the invention as shown to a press having a vertically reciprocating plunger *a* for carrying the upper tool, a carrier lever *b* is pivoted at its upper end on a bracket *c* secured to the front of the machine, the lever being arranged to oscillate in a plane at right angles to the front of the machine. This lever may consist of a pair of similar parts connected by a cross shaft *d* and located at opposite sides of the machine, the construction forming what is

virtually a single lever. The lever or a separately formed subsidiary lever *e* has pivoted on it a link *f* which is also pivoted to the plunger of the press or a part secured to the plunger. The connection with the plunger is effected by an adjustable screw *g*.

To the lower end of the above mentioned lever *b* is pivoted an intermediate point of a second lever *h*. This lever also consists of a pair of elements, connected by a cross shaft *i*, and forming virtually a single lever. Between the inner pair of ends of the two parts of the lever *h* is arranged a hand striking piece *j* which extends across the front of the machine and may consist of a spiral 70 spring, a padded bar or any other suitable element which can strike the hand of the operative without causing injury to the hand. To the outer end of one of the parts of the lever or to a separately formed lever *k*, is pivoted a constraining link *l* which is also pivoted to the frame of the machine or a part carried on the frame. When the plunger is in its upper position the lever *h* carrying the striking piece occupies a position nearly at right angles to the first lever, and the striking piece is in an unobstructive position leaving a clear space between the operative and the upper and lower tools.

As already stated the upper tool (not shown) is carried on the plunger, the lower tool (also not shown) being on the bed *m* of the machine. The link *l* also occupies a nearly horizontal position. The said link is preferably bent, cranked or otherwise 90 suitably shaped to avoid any risk of the operative's fingers being pinched between the link and the part *k*.

During the initial part of the downward movement of the plunger, the link *f* connecting the plunger to the lever *e* causes an outward movement to be imparted to the lever *b*. The form and disposition of the lever *h* and link *l* are such that the inner end of the lever *h* is caused by the motion 95 of the lever *b* to move in a downwardly curved path towards the operative. Should the operative's hands be in the way the striking piece will thrust the hands outwards clear of the tools, and the greater part 100 of the movement is effected before the tools come into action. The position to which the parts are moved is shown by dotted lines in Figure 1. Figure 3 also shows the guard in the operative position. In the return of 110

the plunger the striking piece is returned to its initial unobstructive position shown by Figures 1 and 2.

It will be understood that the constructional details of the guard can be varied to meet different requirements, but in all cases the essential features are as above described. Also the invention is applicable to horizontal as well as vertical machines.

Referring to Figure 4, it is advantageous in some cases to combine with each lever *h* of the arrangement above described, an additional lever *s* mounted at about a right angle to the lever *h*, the two levers *s* at opposite sides of the machine being joined by a hand striking piece *n* similar to the above mentioned part *j*. Figure 4 shows by full lines the disposition of the parts when the plunger is at the top of its stroke. During the descent of the plunger the guard is moved to the position shown by dotted lines. If the operative's hand is lying across the striking piece *n* when the plunger commences its descent, the hand is first raised by the said piece. Immediately afterwards the hand is pushed out of danger by the striking piece *j*. This arrangement is especially useful where, owing to some peculiarity in the configuration of the machine bed adjacent to the tools, the striking piece *j* shown in Figures 1-3 might glide over the hand, when the latter is extended in a horizontal position, and not effect the removal sufficiently early. By means of the additional piece *n* which first lifts the hand, the danger under such conditions is effectively avoided.

Instead of the link *l* shown in Figures 1-4, a fixed slotted member *p* (Figure 5) may be used for imposing the required constraint on the levers *h*, *k*, one end of the lever *k* being caused to slide in the slot. Alternatively a toothed wheel *q* may be secured to one end of the cross shaft *i* connecting the levers *h* and *b*. This wheel is arranged to mesh with a fixed toothed segment *r* as shown in Figure 6. Oscillation of the lever *b* causes the lever *h* to swing between the limits shown by full and dotted lines in that figure. In this arrangement the lever *k* of the preceding mechanisms is not required.

In all cases, however, the pivoted system carrying or forming the guard is mounted on another pivoted system carried on the machine and actuated by motion derived from the machine.

The lever systems *b* and *h* may both be provided with transverse rods *o*, or have attached to them wire meshes to give further protection to the operative, particularly against fragments thrown outwards from the tools.

Where the additional levers *s* shown in Figure 4 are employed, no cross rods or

mesh is arranged between the said levers *s* as the space between them must be left clear for the feeding of the work to the tools.

Having thus described my invention what I claim as new and desire to secure by Letters Patent is:—

1. In hand guards for such machines as presses, stamps, hammers and the like, the combination of a carrier lever system pivotally mounted on the stationary part of the machine, a guard lever system pivoted on the carrier system and normally arranged at an angle to the carrier lever system and immediately adjacent the movable operating part of the machine, a hand striking member on the guard lever system, means for imparting motion to the carrier system from the moving part of the machine to effect outward swinging movement of the carrier system, and constraining means attached to the guard lever system and to another part of the stationary part of the machine to ensure of the guard lever system being swung outwardly in a curved path from the main operating part of the machine simultaneously with the outward swinging movement of the carrier system, the constraining means acting to limit the outward swinging movement of both the carrier and guard lever systems.

2. An arrangement as claimed in claim 1, wherein the means for imparting motion to the carrier lever system consists of an operating lever connected with the carrier lever system, and a link connecting the operating lever to the reciprocating part of the machine.

3. An arrangement as claimed in claim 1, wherein the guard lever system includes a pair of angularly disposed hand striking members, one of which is adapted to raise the hand of the operative and the other to push the hand away from the tools simultaneously with the operation of the reciprocating part of the machine.

4. An arrangement as claimed in claim 1, wherein the guard lever system includes a pair of lever parts situated at angles with respect to each other, and wherein a hand striking member is mounted at the outer end of each of said parts.

5. An arrangement as claimed in claim 1, wherein the constraining means includes an extension lever on the guard lever system, and a constraining link pivoted to the outer end of the extension lever and also pivotally attached to the stationary part of the machine frame.

6. In hand guards for presses and like machines in which a reciprocating part moves relatively to a stationary frame, the combination comprising a pair of carrier levers, a horizontal pivot shaft carrying said levers, a pair of brackets carrying said shaft and respectively mounted on the front

of the machine frame at opposite sides of the reciprocating part, an operating lever on said shaft, a link attached to the operating lever, a screw connecting the link to the reciprocating part, a pair of guard levers, a rod connecting the latter levers to the carrier levers, a hand striking member arranged transversely between the guard levers, a third lever secured to the said rod, a constraining link attached to the said third lever, and means for attaching the constraining link to the machine frame, substantially as described.

7. In hand guards for presses, stamps, hammers and the like, including in combination with the base stationary side portions and movable part of the machine a carrier lever system pivoted on the side portions of the machine at a point remote from the base, a guard lever system pivoted to the outer end of the carrier system and normally arranged at an angle thereto and immediately adjacent the movable part of the machine when the latter is in a retracted position, a hand striking member on the guard lever system, means for imparting motion to the carrier system on the side portions of the machine so that the carrier system will be swung outwardly therefrom, and constraining means cooperating with the motion imparting means and attached to the guard lever system and to the side portions of the machine at a point on the side guard lever system opposite the base so that the guard lever system will be swung outwardly in a curved path from the main moving part of the machine simultaneously with the extending of this part of the ma-

chine and the outward movement of the carrier lever system, substantially as and for the purposes set forth.

8. In hand guards for such machines as presses, stamps, hammers and the like, the combination with a main stationary part of the machine, spaced side portions extending from the main stationary part of the machine and the main reciprocating part of the machine, a carrier lever system pivoted at its inner end to the side portion of the machine remote from the main stationary portion and also rearwardly of the main reciprocating part of the machine, a guard lever system pivoted to the outer end of the carrier lever system and normally arranged at an angle to the carrier lever system and immediately in advance of the main reciprocating part of the machine when the latter is in a retracted position, means for imparting outward swinging movement from the carrier lever system to the inner portion of the reciprocating part of the machine, and constraining means cooperating with the carrier system and attached to the guard lever system at one end and to the side portions of the machine adjacent the reciprocating part of the machine when the latter is in retracted position to ensure of the guard lever system being swung in a curved path outwardly from the reciprocating part of the machine simultaneously with the operation of this part of the machine at the outward swinging movement of the carrier system.

In testimony whereof I have signed my name to this specification.

JOHN POUNTNEY UDAL.
